UNITED STATES PATENT OFFICE.

ABBOTT L. PENNIMAN, JR., OF BALTIMORE, MARYLAND, ASSIGNOR TO WHEELER CON-DENSER & ENGINEERING COMPANY, OF CARTERET, NEW JERSEY, A CORPORATION OF NEW JERSEY.

FEED-WATER HEATER.

Application filed June 6, 1925. Serial No. 35,278.

In power plant practice the advisability of heating the feed water to prevent boiler strains, and to increase efficiency by the requirements for smaller quantities of fuel has 5 been recognized for a long period. When the practice of heating feed water was first taken up it was customary to heat the feed water by utilizing the exhaust steam from auxiliary apparatus. In this practice however, comparatively little economy was effected, later the exhaust from generator driven house turbines and small auxiliary turbines was then utilized for heating the feed water. Subsequently, and at the present time it has been found more effective and 10 decidedly more efficient to heat the feed water through a suitable medium by steam extracted from various stages of the more efficient main turbines.

Experiments have shown that by employing a plurality of feed water heaters of a certain type a maximum efficiency is obtained by attaining a final temperature of the feed water, which temperature if exceeded decreases the efficiency. It has also been found that the temperature at which the greatest efficiency is a maximum, depends upon the number of heaters employed; generally speaking the efficiency being substantially proportionate to the number of heaters employed. In the use of these heaters the exhaust steam from a corresponding number of stages of the turbine is bled and carried to the several heaters for raising 30 the temperature of the feed water which is conveyed in series through the heaters, irrespective of the number of the same which may be employed. In selecting the bleeding points for conveying the steam from the 35 several stages of the turbine, it is advisable of course to select those points at which the greatest efficiency may be obtained. These bleeding points are found to be such that the total temperature rise in the feed water is substantially divided equally between the heaters employed.

The feed water heater to which my invention relates is of the type and for the use to which reference has hereinbefore been made. This feed water heater preferably 50 comprises a shell adapted to be placed in a vertical position, and provided with a steam inlet and return inlet for the condensate or condensed steam, and a drain from which the condensate or condensed steam is

trapped or otherwise conveyed to the next succeeding heater in the series, as employed. Within the shell I also employ a transversely disposed baffle plate, and a partition wall, which latter acting with a portion of the 60 baffle plate provides for an air cooler chamber within the shell. The feed water heater also includes a plurality of suitably mounted, and preferably U-shaped tubes, together with means for conveying the feed water 65 to and from the said tubes, and a plurality of staggered baffle plates in the condensing space of the heater for causing the steam to travel a sinuous path with a maximum velocity, so as to carry with it the air and non- 70 condensable vapors which thereby are conveyed to the air cooler chamber, and from which they are vented or conveyed away by a suitable air pump, or otherwise. The construction furthermore, is such that the 75 water box, the tube plate, the tube secured thereto, and the other parts associated therewith are removable as a unit from any particular shell, so that the same are interchangeable with other heater shells. These 80 and other features of the heater will be hereinafter more particularly described.

In the drawing:

Fig. 1 is a partial elevation and central longitudinal section of a feed water heater 85 made in accordance with my invention.

Fig. 2 is a central longitudinal section taken at right angles to the position of the parts as shown in Fig. 1.

Fig. 3 is a sectional plan taken on line 90 3—3, Fig. 1.

Fig. 4 is a plan on line 4—4, Fig. 2, with the tube plate, tubes and parts associated therewith removed.

Referring particularly to the drawing the 95 feed water heater made in accordance with my invention comprises a shell 10, which is preferably cylindrical and made of steel, although as will be understood it may be formed in other shapes and constructed of 100 any other suitable material. This feed water heater when in use is adapted to be placed in a vertically disposed position, and at the upper end of the shell the same is provided with a flanged rim 11. At the lower end of 105 the shell there is a bottom or base 12, provided centrally or otherwise with a drain or outlet 13. As will be understood the rim 11, and the bottom 12 may be welded or otherwise suitably connected to the shell. In 110

a suitable position, preferably adjacent the lower end thereof the shell is provided with a steam inlet 14, and in another position, somewhat more removed from the bottom 5 with a return inlet 15, furthermore, the shell is also provided with an air or other non-condensable vapor outlet 16, which is suitably placed so as to communicate with the air cooler chamber to which reference is 10 hereinafter made.

Interiorly the shell is provided with a longitudinal partition wall 17, which may be suitably connected thereto, and preferably divides the interior of the shell into compartments in the portion of substantially twenty (20%) and eighty (80%) per cent. 15 The top 18 of the partition wall lies appreciably distant from the upper end of the shell, so as to leave a passage between the same and the tube plate as hereinafter described. At the lower end this longitudinal partition wall 17 is suitably connected to a transverse baffle plate 19, which as indicated may be connected to and supported by suitable brackets or lugs 20 or otherwise; that portion of the transverse baffle plate 19 lying between the shell and the longitudinal partition wall is imperforate, while that portion of the transverse baffle plate 19, 25 extending beyond the longitudinal partition wall is provided with a series of apertures 21, by which the condensed steam or condensate, or a large portion thereof is caused to drip through the incoming steam, to which reference will be hereinafter made. The transverse baffle plate 19 extends from one portion of the shell, substantially three-quarters of the diameter of the shell toward the opposite side thereof. The longitudinal partition wall and a portion of the transverse baffle form an air cooler chamber or 40 space 22. Exterioly the shell may be provided with suitable angle brackets 23 and 24 in oppositely disposed position by which 45 the feed water heater is supported upon a suitable base or foundation provided for this purpose.

The feed water heater also includes a tube plate 25, of a diameter substantially equal 50 to that of the flanged rim 11; suitably secured in this tube plate and at their respective ends there is a plurality of tubes 26. These tubes 26 are U tubes, and the ends thereof may be connected to the tube plate 55 in any arrangement and by any suitable means. By the use of the U tubes connected at their ends in a unitary tube plate, it will be understood that a free expansion of the tubes is possible. Within the condenser 60 chamber of the heater I also prefer to employ a plurality of transversely placed staggered baffle plates 27. The tubes 26 pass through apertures provided therefor in these baffle plates 27, and the baffle plates are supported by rods 28, or otherwise, which are 65

connected to and suspended from the tube plate in any suitable manner. These baffle plates 27 are so arranged in the heater as to cause the steam to travel a sinuous path to enhance the travel of the steam, and consequently to assist in conveying the air and other non-condensable vapors to the upper portion of the heater, where they pass over the upper edge of the longitudinal partition wall 17 to the air cooler chamber 22. 70

The feed water heater also includes the customary water box 29, which may be made of steel or cast iron or other material, depending upon the pressure which in practice the same must withstand. This water box 29 is flanged in the customary manner and is provided with a feed water inlet 30, and a feed water outlet 31. Within the water box there is a centrally disposed partition wall 32, extending across the same, and a transverse partition wall 33, extending half way across the same, these partition walls dividing the interior of the water box into compartments indicated at 34, 35 and 36. This construction provides a four pass 80 arrangement. It may be desirable however, in some instances to employ either a two pass or a six pass, or even an eight pass construction. Also as is customary the water box is provided with a cover or bonnet 37, 85 connected thereto by suitable bolts or otherwise, and for the purpose of reinforcing the parts. The interior of the water box may also be fitted with suitable spaces 38, which in any desired manner are preferably associated with the bolts, by which the bonnet, the water box and the tube plate may be connected to each other. Also as is clearly indicated in Figs. 1 and 4 of the drawing that portion of the transverse baffle plate 19, 90 forming the bottom of the air cooler chamber may be fitted with a suitable trap 39, by means of which any steam which may be conveyed over into the air cooler chamber and therein condensed, is trapped back to 95 the incoming steam space and the condensate chamber 40, immediately below the same. 100

It will be noted that the feed water heater is preferably so arranged that the inlet connection 30 is on the same side as the air cooler chamber 22, in order that the tubes in the air cooler chamber are on the colder side of the multiple pass arrangement. 105

The other devices which may be included in the system are the condensing equipment 110 serving the steam jet air pumps, oil coolers, for cooling the turbine bearing oil, evaporator condensers and such other heat exchange apparatus as may be desirable. In practice it may be advantageous to introduce the make-up into the main condenser after it has passed through the oil cooler or generator air cooler. This make-up together with condensate from the main condenser will then pass to the hot well where, if de- 115 120 125 130

sired, it may be deaerated by the introduction of all or a portion of the hot drips from the bleeder heaters. This deaerated water is then pumped through the several pieces 5 of heat exchange apparatus together with the bleeder heaters from which it is delivered to the boilers.

The feedwater heaters may be conveniently employed in batteries of 2, 3, 4 or more, depending on the feedwater temperature desired and the general arrangement of the station heat balance. As, for example, a 10 9-stage impulse turbine can be arranged for bleeding from the 3rd, 5th and 7th stages. 15 Steam bled from the 3rd stage is conveyed to the 1st feedwater heater; the steam bled from the 5th stage of the turbine is conveyed to the 2nd feedwater heater, and steam bled from the 7th stage of the turbine is conveyed 20 to the 3rd feedwater heater. The condensed steam, or condensate, from the 1st feedwater heater may then be trapped back to the 2nd feedwater heater; the condensed steam, or condensate, from the 2nd feedwater heater 25 may be trapped back to the 3rd feedwater heater, and the condensed steam, or condensate, from 3rd feedwater heater may be passed through a heat exchange device, and thence to the hot well of the main condenser 30 where it may be used for deaerating the feedwater sufficiently to remove any entrained air or non-condensable vapor so that the necessity of any special deaerating apparatus is eliminated.

35 It will be understood the use of the transverse baffle plate 19 is particularly desirable, for example, in the 2nd and 3rd feedwater heaters, where the steam bled from the 3rd and 5th stages of the turbine is superheated, 40 because the steam as it enters the feedwater heater passes directly beneath this transverse baffle plate, and consequently the steam passes through the water of condensation, and thereby the superheat is removed from 45 the steam. The superimposed series of baffle plates of the steam chamber in each feedwater heater as hereinbefore stated, are also arranged so as to maintain a high steam velocity around the tubes, which causes the air 50 and other non-condensable vapors to be carried to, or toward the top of the feedwater heater, and thence over the upper edge of the longitudinal partition wall, and into the air chamber where the air and other non-condensable vapors may gravitate toward the 55 bottom of the air cooler chamber, and from which they are vented or removed by an air pump or otherwise, as hereinbefore stated. Any steam which may find its way into the 60 air cooler chamber and is there condensed is trapped back into the heater shell by means of the trap 29, as hereinbefore described.

It is furthermore to be noted, that in the 65 feedwater heater as constructed in accordance with my invention, the tube plate, the

tubes, the water-box and the parts associated therewith when connected form a unit which may be removed from any condenser shell, as such, and replaced in the condenser shell, or set in any other condenser shell, so that 70 the tube plate, the tubes and water-box units are interchangeable in various shells for heaters of like capacity.

I claim as my invention:

1. In a feed water heater, a cylindrical 75 vertically placed shell, a tube plate at the upper end of the shell, a plurality of U tubes suspended at their ends from the said tube plate and extending downwardly therefrom, means for admitting steam adjacent the lower end of the shell and below the lower ends of the said U tubes, a water box associated with the tube plate, an inlet connection for admitting feed water to the water box, and an outlet connection for conveying the feed 80 water from the water box.

2. In a feed water heater, a cylindrical 85 vertically placed shell, a tube plate at the upper end of the shell, a plurality of U tubes suspended from the tube plate and extending 90 downwardly therefrom into the said shell, means for admitting steam to the shell beneath the lower ends of the said U tubes, a transverse baffle plate lying between the steam inlet and the adjacent lower ends of 95 the U tubes and extending partially across the said shell, and means for conveying feed water to and away from the said U tubes.

3. In a feed water heater, a cylindrical 100 vertically placed shell, a tube plate at the upper end of the shell, a plurality of U tubes suspended from the tube plate and extending 105 downwardly into the said shell, a steam inlet connection through the shell below the lower ends of the said U tubes, a transverse baffle plate lying between the steam inlet and the lower ends of the U tubes and extending partway across the said shell, a longitudinal partition wall extending upwardly from the said baffle plate and dividing the interior of 110 the shell into a steam condenser chamber and an air cooler chamber, and means for conveying feed water to and away from the said U tubes.

4. In a feed water heater, a cylindrical 115 shell, a steam inlet adjacent one end of the shell, a tube plate at the opposite end of the shell, a plurality of U-shaped tubes secured at their ends in the said tube plate 120 and extending from the same to points adjacent the said steam inlet, a transverse baffle plate extending part way across the shell interiorly thereof, between the inner ends of the said U-tubes and the said steam inlet, a longitudinal partition wall extending 125 from the said transverse baffle plate to a point adjacent the tube plate, and with a portion of the baffle plate and the said shell providing for an air cooler chamber, an air outlet connection from the said air cooler 130

chamber, and means for conveying feed water to, and from the said tubes.

5. In a feed water heater, a cylindrical shell, a steam inlet adjacent one end of the shell, a tube plate at the opposite end of the shell, a plurality of U-shaped tubes secured at their ends in the said tube plate and extending from the same to points adjacent the said steam inlet, a transverse baffle plate extending part way across the shell interiorly thereof, between the inner ends of the said U-tubes and the said steam inlet, a longitudinal partition wall extending from the said transverse baffle plate to a point adjacent the tube plate, and with a portion of the baffle plate and the said shell providing for an air cooler chamber, an air outlet connection from the said air cooler chamber, the said transverse baffle plate being perforated in that portion of the same which extends beyond the said transverse partition walls, whereby the incoming steam is caused to pass through the water of condensation as the same drips from the perforated portion of the transverse baffle plate, and means for conveying feed water to, and from the said tubes.
6. In a feed water heater, a cylindrical shell, a steam inlet adjacent one end thereof, a tube plate at the other end thereof, a transverse baffle plate extending part way across the shell adjacent the said steam inlet, a plurality of U-tubes connected in and extending from the tube plate to points adjacent the said baffle plate, a longitudinal partition wall extending from the transverse baffle plate to a point adjacent the tube plate, and providing an air cooler chamber and a condenser chamber within the shell, an air outlet connection communicating with the air cooler chamber, a series of staggered baffle plates through which the said tubes pass in the condenser chamber, and by which the steam is caused to travel in a sinuous path around the said tubes and to assist in conveying the air and non-condensable vapors to the tube plate end of the heater, where they then enter the air cooler chamber, means whereby steam which may be condensed in the air cooler chamber is trapped back within the heater shell, and means for conveying feed water to, and from the said tubes.
7. In a feed water heater, a cylindrical shell, a tube plate at the upper end of the shell, a plurality of U tubes suspended from the tube plate and extending into the said shell, a steam inlet connection through the said shell below the lower ends of the said U tubes, a return inlet connection at the lower end of the said shell, a condensed steam outlet connection adjacent the bottom of the said shell, a transverse baffle plate above the said steam inlet connection and below the lower ends of the said tubes and extending partway across the said shell, a longitudinal partition wall extending upwardly from the said transverse baffle plate and dividing the tube space in the shell into a steam condensing chamber and an air cooler chamber, a plurality of staggered baffle plates surrounding the U tubes in the said steam condensing chamber, a water box associated with the tube plate, and means for conveying feed water to and from the said water box.
8. In a feed water heater, a cylindrical vertically disposed shell, a bottom at the lower end of the shell, a condensed steam outlet in the said bottom, a steam inlet connection adjacent the lower end of the shell, a return inlet connection also adjacent the bottom of the shell, a transverse baffle plate extending part way across the shell interiorly thereof, and between the said steam inlet connection and return inlet connection, a tube plate at the upper end of the shell, a plurality of U-tubes connected in and extending downwardly from the said tube plate to points adjacent the said transverse baffle plate, a partition wall extending from the said transverse baffle plate upwardly to a point adjacent the said tube plate, dividing the interior of the shell into an air cooler chamber and a condenser chamber, an air outlet connection in connection with the air cooler chamber, a plurality of staggered baffle plates in the said condenser chamber, and through which the said U-tubes therein pass, means for supporting the said staggered baffle plates, a water-box, and connections for conveying feed water to, and from the said water-box in order that the same may be caused to traverse the said U-tubes.

Signed by me this 21 day of May, 1925.

ABBOTT L. PENNIMAN, JR.
